J. Nicolet,
Anti-Friction Roller.
Patented June 12, 1835.

June 12, 1835

Julian Nicollet of Pittsburg Pennsylvania
Lellers Patent

The subscriber is found to in these letters Patent and現在, had of
the same Containing a description on the merits, of the said Julian
Nicollet of his, improvement in machinery called the antifriction
wheel, particularly applicable to Steam Boats.

To all to whom these presents shall come. Be it known that I
Julian Nicollet of the City of Pittsburg in the State of Pennsylvania -
have invented a new and useful improvement in machinery called
antifriction wheels, particularly applicable to Steam Boats, and that
the following is a full and exact description of the construction and op-
eration of the same. The friction wheels, which I use, are made of cast
iron or any other suitable material, in the form of a short hollow cylinder
with one end closed and the other open, or in other words, of a flat
wheel with a narrow flange projecting at right angles from its cir-
cumference, the dimensions being varied to suit circumstances. At
the center a square opening is left for the shaft which for strength is also
surrounded by a thick flange. The shaft on which the wheel is made
permanent, and which should be of well tempered steel, passes through
the center opening and projects sufficiently far on both sides, to form the ju-
nals or bearings of the wheel. Although the bearings may be varied, those
which I prefer are as follows; an upright plate of iron with a octangular
foot or ear to secure it by screws, is made fast to the top of the bearing timber
or a straight plate when that form will suit the situation best, is to be
used. in the upper end a hole is made for one journal of the friction wheel
a suitable box may be attached thereto, the other journal being sup-
ported in a similar hole or box, in the upper end of a short iron cap, or
rectangular iron, secured firmly to the back of the plate, just mention-
ed. the wheel lying between them, with the cavity towards the plate.
A hole is made in the plate of sufficient size, to admit and allow
to play freely, the shaft of the balance wheel or other shaft, to be no-
ticed. If the friction, its lower side or end extending a short distance

below the flange of the friction wheel, by which means the shaft is caused to bear on the inner surface of the flange, and the friction of the same is reduced or diminished in the proportion which the diameter of the flange bears to the diameter of the journal of the friction wheel and shaft joint by. On the end of the shaft a journal is turned as truly cylindrical as possible, being well tempered, and something shorter than the depth of the flange, the square shoulder of the shaft thus formed, prevents the end of the journal from coming in contact with the plane of the shaft, and the sides of the hole in the plate serve to check the lateral movement of the shaft, to receive the pressure of which lateral friction roll as attached to the plate may be employed. Then wheels I apply, one at each end of the shaft of water wheels, or balance wheels, used for propelling mills and factories, also the paddle wheels and balance wheel of boats to be propelled by steam or other power, and have found by a variety of experiments, that this application effects an immense saving of power and expence of machinery, and particularly when applied to Steam Boats, of additional weight of machinery, and loss of time consequent upon the employment of Engines, and Boats far more powerful than what would be required with my improvement.

Now I do not claim to have invented the friction wheel described herein, but its application to the specific improvement herein described. In testimony that the foregoing is a true specification of my said improvement, I have hereunto set my hand at the City of Washington this 30th day of May 1835.
